[57] CLAIM

The ornamental design for condiment grinding device, as shown and described.

DESCRIPTION

FIG. 1 is a bottom perspective view of a condiment grinding device showing my new design;

FIG. 2 is an exploded bottom perspective view thereof;

FIG. 3 is an exploded top perspective view thereof;

FIG. 4 is a bottom plan view of the inner portion thereof, shown separately for clarity of illustration;

FIG. 5 is a top plan view of the inner portion thereof, shown separately for clarity of illustration;

FIG. 6 is a cross-section taken along line 6—6 FIG. 4;

FIG. 7 is a bottom plan view of the outer portion thereof, shown separately for clarity of illustration; and

FIG. 8 is a cross-section taken along line 8—8 of FIG. 7.

FIG. 1.

FIG. 2.

FIG. 3.

FIG. 4.

FIG. 5.

FIG. 6.

FIG. 7.

FIG. 8.
